[57] CLAIM

The ornamental design for a set of bottles, as shown and described.

DESCRIPTION

FIG. 1 is a top, front and left side perspective view of one of the bottles that comprise my new design for a set of bottles;

FIG. 2 is a top, rear and right side perspective view thereof; FIG. 3 is a top plan view thereof;

FIG. 4 is a bottom plan view thereof;

FIG. 5 is a front elevational view thereof;

FIG. 6 is a left side elevational view thereof;

FIG. 7 is a right side elevational view thereof;

FIG. 8 is a rear elevational view thereof;

FIG. 9 is a perspective view of the set of bottles comprising three of the bottles shown in FIGS. 1-8;

FIG. 10 is a top plan view thereof;

FIG. 11 is a bottom plan view thereof;

FIG. 12 is a front elevational view thereof;

FIG. 13 is a left side elevational view thereof;

FIG. 14 is a right side elevational view thereof; and,

FIG. 15 is a rear elevational view thereof.

The individual bottle shown in FIGS. 1 through 8 is shown separately for clarity of illustration.
